UNITED STATES PATENT OFFICE.

GEORGE W. MILLER, OF ROCHESTER, NEW YORK.

WOODEN-SOLE SANDAL.

1,187,005.

Specification of Letters Patent. Patented June 13, 1916.

Application filed May 27, 1915. Serial No. 30,853.

To all whom it may concern:

Be it known that I, GEORGE W. MILLER, a citizen of the United States, residing at Rochester, in the county of Monroe and State of New York, have invented certain new and useful Improvements in Wooden-Sole Sandals, of which the following is a specification.

The object of this invention is to produce a sandal comprising a wooden sole and an upper or fastening therefor made of canvas or leather.

This and other objects of the invention will be fully illustrated in the drawings, described in the specification, and pointed out in the claims at the end thereof.

In the drawings, Figure 1 is a perspective view of the sandal viewed from the left side thereof. Fig. 2 is a perspective view of the sandal viewed from the opposite side. Fig. 3 is a vertical section through the heel of the sandal the section being taken on the line 3^x-3^x of Fig. 1. Fig. 4 is a perspective view of the wooden sole of the sandal.

Fig. 5 is a perspective view of the sole of the sandal with the upper in process of being attached thereto. Fig. 6 is a bottom plan view of the sole of the sandal showing the rubber plugs in place on the sole.

In the accompanying drawings like reference numerals indicate like parts.

This sandal is made up of a wooden sole 1 having an upper attached thereto, which upper is made up of two parts, the main body part being indicated by the reference numeral 2 and the strap indicated by the reference numeral 3. The wooden sole 1 is made preferably of a single piece of wood turned up to the proper shape in a last man-

chine, the bottom of it being made with a flat heel and rounded half sole substantially of the outline followed for the ordinary types of shoes and the top of it is formed so as to fit the bottom of the foot.

The top of it is also provided with an elevation 4 which is curved to fit the arch of the foot and is intended as an arch support.

On the side the wooden sole is recessed at 5, 6 and 7 and is grooved immediately below these recesses as is shown at 8 and 9. These grooves and recesses are intended to receive the lower part of the upper which is fastened therein by staples or binding wire or by a combination of both as will now be described.

As is indicated in Figs. 3 and 5 the up-

per is laid against the wooden sole with the fastening edges thereof overlapping the grooved and recessed places, the upper being placed upside down and with the wrong side out. The forward part of the upper is fastened in place in the groove 8 by means of a long wire staple 10, which is of nearly the same length as the groove, which staple engages with the upper about a quarter of an inch from the edge thereof and forces it into the groove. The staple 10 may be reinforced by small staples 11 and 12. This fastening is illustrated in the left hand end in Fig. 5.

The rear end of the upper is fastened to the sole above the heel in the manner shown in the right hand end in Fig. 5. At the rear end a binding wire 13 is used having a staple 14 fastened to each end thereof. The upper 2 is laid in place and the staple at one end of the wire is driven into the groove preferably through the upper about a quarter of an inch from the edge thereof fastening the upper and one end of the binding wire at that point. This binding wire is then drawn around the groove forcing the upper into the groove about a quarter of an inch of the upper being left projecting above the groove. The free end of the binding wire and the upper is then fastened into the groove on the other side of the heel by driving the staple through the upper into the groove. This binding wire is drawn tight so that it will securely hold this part of the upper in place in the groove which extends around the upper edge of the heel. This binding wire may be held more securely in place by staples such as are shown at 15, 15, etc., which staples are driven into the grooves and serve to hold both the wire and upper in place. After the upper has thus been fastened in place it is then inverted or turned right side up on the sole. This brings it to the position shown in Figs. 1 and 2.

It will be understood that the strap 3 is fastened on the opposite side of the sole in the same manner in which the forward part of the upper is fastened. The upper is provided with buckles shown in Fig. 1 with which the tongues provided, one on the upper and the other on the strap, are adapted to engage and by which the upper may be closed around the foot. The recesses 5, 6 and 7 are adapted to receive the upper therein after it has been turned up to final

position permitting it to rest snugly in place in the sole. The depth of the recesses being about equal to the thickness of the material of the upper. The bottom of the sole is recessed with suitable recesses and in these recesses are placed rubber plugs 17 such as are shown in Fig. 6.

I claim:

1. A sandal or the like comprising an upper, and a one-piece wooden sole to the side edges of which the upper is secured, said sole forming both an outsole and an insole and having its top surface elevated at one side thereof above the surface of the oppo-

site side to fit under and support the arch 15 of the foot.

2. A sandal or the like comprising a wooden sole having grooves in the edges thereof, upper parts the ends of which are turned inwardly and upwardly in said 20 grooves, and fastening wires engaging said ends and covered by said upper part and extending lengthwise in the grooves and secured to the sole.

In testimony whereof I affix my signature.

GEORGE W. MILLER.
